UNITED STATES PATENT OFFICE.

HARLOW R. BROWN, OF YONKERS, NEW YORK, ASSIGNOR TO PHILIP STROBEL & SONS, INC., OF NEW YORK, N. Y.

CONVERTIBLE TABLE.

1,212,897.

Specification of Letters Patent. Patented Jan. 16, 1917.

Application filed March 29, 1915. Serial No. 17,653.

To all whom it may concern:

Be it known that I, HARLOW R. BROWN, a citizen of the United States, and a resident of Yonkers, county of Westchester, and State of New York, have invented certain new and useful Improvements in Convertible Tables, of which the following is a specification.

This invention relates to improvements in convertible tables.

10 By the use of my invention I am enabled to produce a table, convertible with great rapidity and by very simple and inexpensive means, from a type with a square or polygonal top to a round-top type and vice versa, and in which the hinged portions or extension leaves will, when in extended position, not only be securely supported but will be held against movement or strains in the opposite directions by means of a traveling 15 connection of the supporting element with the hinged leaf. All strains which may, in the carrying of the table be caused by taking hold of the extended hinged leaves and which would, under ordinary circumstances 20 be applied to the hinges, will be compensated for, the retention of the leaves against the support being accomplished simultaneously with the movement of the support to supporting position, so that any movement 25 of the supporting element to support the leaf or leaves will cause a corresponding retention or locking of the extension leaves to the support. Furthermore, when the extension leaves are moved into folded position, I provide in the support a simple locking 30 dog cut out from and lying, when in unused position, within the planes of said supporting element, for retaining the extension leaves in such folded position.

35 I will now describe the preferred embodiment of my invention and then point out the novel features in claims.

In the accompanying drawings in which similar reference characters designate corresponding parts throughout the several views, Figure 1 is a bottom view of a table embodying my invention, two of the extension leaves being shown in folded position and two in extended position; Fig. 2 is an en-

larged section on the line 2—2 of Fig. 1 50 showing an extension leaf in folded position; Fig. 3 is a section on the line 3—3 of Fig. 1; Fig. 4 is an enlarged section of an extension leaf and support similar to that illustrated in Fig. 3, the leaf being in extended position; Fig. 5 is a modified form of my improved device for providing a traveling locking connection or engagement between the support and leaf; Fig. 6 is a fragmentary bottom view of the device shown in 55 Fig. 5; Fig. 7 is a fragmentary section on the line 7—7 of Fig. 1, showing a simple flat spring which may be employed if desired to retain the support in its full open position.

Referring now to these drawings, 1 designates the body portion of the table-top which, as shown, is square in conformation and is supported by a rectangular supporting-frame 2, which is provided at each corner with legs 3—3^a—3^b—3^c. The square 60 body portion 1 extends as shown outwardly from the frame 2 a sufficient distance to permit the folding thereunder of extension leaves 4 which are suitably hinged by hinges 5 to the edges of the body portion and which 65 when extended, will change the conformation of the table to circular but when folded 70 will lie flat against the under surface of the body portion so as to be entirely out of the 75 way.

By my invention, I provide a supporting member 6 which, as shown, is hinged to the frame 2 at 6^a and is adapted to be swung in the arc of a circle from a position parallel with a side of the frame to its leaf-supporting position at an angle thereto, and said supporting member will by means of a traveling connection with the leaf automatically and during its movement beneath the leaf to 80 said supporting position, engage or grip the extension leaf from beneath. My preferred 85 means for providing said traveling connection between said supporting member and the leaf to be supported consists in providing the end of the supporting member with a rigid gripping-iron 7 suitably secured at 90 the outer edge thereof and preferably bent as shown in Figs. 3 and 4 to have a hooked 95

portion 7^a which preferably extends into an arc-shaped slot 8 formed concentrically with the arc of movement of said supporting element, the said slot preferably being formed by cutting or depressing in the bottom of the extension leaf and also in the bottom surface of that portion of the body of the table top 1 that extends beyond the frame 2 an arc-shaped groove 8^a preferably co-extensive 10 and concentric with the arc of movement of said supporting member 6, and securing to overhang one edge of said groove in the leaf portion thereof an arc-shaped bearing iron or track 9, which is preferably set in flush 15 with the bottom surface of the leaf and is engaged by the said hooked portion 7^a at all times during the movement of the supporting member beneath said extension leaf.

Another form of traveling connection between the leaf and supporting element is shown in Figs. 5 and 6 in which, instead of the depressed groove 8^a, I provide an arc-shaped angular member 10 suitably secured by screws or the like to the bottom of the table and having a flange 10^a spaced from the table to form a slot 11 into which an end portion 12^a of a gripping iron 12, hooked or bent in a direction opposite to the first mentioned hook 7^a, extends and at all times 30 bears against the flange 10^a.

In either form of said invention, it will be obvious that when a person in carrying a table from one place to another grips the outer edge of the extension leaf, the weight 35 of the table will through the traveling connection be supported by the supporting members, and all such strains which, in such a carrying operation, is usually placed upon the hinges 5, will be provided for by the supporting member which is, of course, of such rigid construction as to be fully capable of taking care of such strains. Furthermore, it will be seen that so soon as the 40 supporting member begins its supporting function it immediately begins its gripping function, and if, for example, through carelessness of a waiter in a hotel or other person handling the table, the supporting member is not moved into its fully open position 45 50 the leaf will be retained against upward strain to the same extent that it is supported against downward strain and no ill results will follow.

To apprise the user of the table when the 55 supporting member is in full-open position, I provide suitable stops and also preferably locate in the path of movement of the supporting member a simple flat spring 13 having its hooked free end 13^a reciprocating in a slot 14 to permit automatic latching of such supporting member in moving the same 60 into supporting position but to compel manual manipulation to move said member to disengaging position.

I will now describe my preferred means 65 for retaining the leaves folded up against the bottom of the body portion of the table top or in a plane parallel thereto.

Obviously, when it is desired to change the shape of the table from round to square, 70 the supporting member will be swung out from under the same whereupon the leaf may then be dropped and moved upwardly so as to lie flat against the under surface of that portion of the table top body which 75 extends beyond the frame, and in order to retain such leaf in such completely folded position, I preferably provide a pivoted dog or bolt member 14 which is preferably cut out from the body of the said supporting 80 member and is seated within said member. Said dog is preferably of the same material as said supporting and retaining member, is pivoted therein at 14^b to swing beneath the table leaf which is adapted to fold into 85 proximity with said supporting member, and said dog or latching portion is provided with beveled edges 14^a adapted to coöperate with beveled edges 14^a in the seating slot of the supporting member so as to provide suitable stopping surfaces when the same is moved out of latching engagement and into 90 the planes of said supporting member.

Having described my invention, I claim:

1. In a convertible table the combination 95 with a suitable frame, a table top having relatively stationary extensions extending beyond said frame, an extension leaf hinged at the edges of each stationary extension and adapted to fold in a semi-circular path 100 beneath said extension, a leaf-supporting bracket hinged to swing in a horizontal direction only and having its upper edge substantially flush with the under surfaces of the stationary extension and folding leaf 105 when the latter is in extended position, an arc-shaped track in the under surface of the extension leaf and a registering arc-shaped track in the under surface of the stationary extension, and a bearing iron secured to the 110 leaf-supporting bracket and bearing on the upper surface of the track in the under surface of the extension leaf when the same is extended.

2. In a convertible table the combination 115 with a suitable frame, a table top having relatively stationary extensions extending beyond said frame, an extension leaf hinged at the edges of each stationary extension and adapted to fold in a semi-circular path 120 beneath said extension, a leaf-supporting bracket hinged to swing in a horizontal direction only and having its upper edge substantially flush with the under surface of the stationary extension and folding leaf 125 when the latter is in extended position, an arc-shaped track in the under surface of the extension leaf, a registering arc-shaped

track in the under surface of the stationary extension, and a dog pivotally mounted in said leaf-supporting bracket and adapted to engage said leaf when in its folded position.

In witness whereof, I have signed my

name to the foregoing specification in the presence of two subscribing witnesses.

HARLOW R. BROWN.
